UNITED STATES PATENT OFFICE

109,812

DESIGN FOR A DUPLICATING MACHINE

Willis A. Kropp, Oak Park, Ill., assignor to Ditto,
Incorporated, Chicago, Ill., a corporation of
West Virginia

Application November 11, 1937, Serial No. 72,800

Term of patent 7 years

To all whom it may concern:

Be it known that I, Willis A. Kropp, a citizen of the United States, residing at Oak Park, in the county of Cook and State of Illinois, have invented a new, original, and ornamental Design for a Duplicating Machine, of which the following is a specification, reference being had to the accompanying drawing, forming part thereof which is a perspective view of a duplicating machine showing my new design.

The opposite side of the machine is substantially the same in appearance as the side shown except for the differences incident to the presence of the handles and other operating parts at the near side.

I claim:

The ornamental design for a duplicating machine as shown and described.

WILLIS A. KROPP.
